F. A. WEGNER.
DUST COLLECTOR.
APPLICATION FILED APR. 22, 1916.

1,190,051.

Patented July 4, 1916.

UNITED STATES PATENT OFFICE.

FREDERICK A. WEGNER, OF SILVER CREEK, NEW YORK.

DUST-COLLECTOR.

1,190,051.

Specification of Letters Patent.

Patented July 4, 1916.

Application filed April 22, 1916. Serial No. 92,893.

To all whom it may concern:

Be it known that I, FREDERICK A. WEGNER, a citizen of the United States, residing at Silver Creek, in the county of Cattaraugus and State of New York, have invented certain new and useful Improvements in Dust-Collectors, of which the following is a specification.

This invention relates to dust collectors 10 in which dust or other matter held in suspension in air is separated therefrom by the rapid whirling of the laden air in a separating chamber.

The invention subject of the present application is in the nature of improvements 15 upon the invention subject of an application filed by me March 2, 1916, Serial Number 81,696, and the broad objects of the present invention comprise the same objects 20 as the application referred to, such objects being to provide a machine of the character specified in which entrance of dust laden air into the air outlet is practically eliminated, and the separating action is rendered thor- 25oughly effective.

Machines of this general description have long been in use in this art but in their use many difficulties and objections have been encountered. The drum is usually 30 composed of an upper cylindrical portion and a lower conical portion, the cylindrical portion being provided with a deck or cover in which is a suitable opening for the escape of air and the conical portion being pro- 35 vided at its lower end, or apex, with a suitable opening for the escape of dust.

In the air escape opening a tubular guard or air escape tube has been mounted and it has been found that owing to the whirl or 40 vortex made by the air, that the tubular guard, in order that it shall offer the least obstruction to the escaping air, should be located eccentrically with relation to the axis of the deck, and machines of this class 45 have been constructed with many movable parts, for this purpose which are liable to dislocation and disarrangement.

In successful machines of the character specified, the laden air under pressure, generally by means of a fan, is introduced tangentially into one side of the separating chamber and travels in a circular path in contact with the walls of the chamber, until nearly a complete revolution is made, when 55 the air from the tangential entrance is encountered which acts as a barrier to the

further true circular travel in the same plane and the natural force of gravity also acts to cause the current of laden air to drop lower into the chamber. Under these influences, the current of air whirling around in the chamber, tends, when, at the end of the first complete revolution, it encounters the incoming air at the entrance as stated, to pass around partially below the first circle of air, and the continued whirling of the air gradually passes to lower planes thereby forming a whirl or vortex of such air, of substantially the form of an inverted cone.

Owing to the obstruction of the current at the entrance the vortex or cone of whirling air is forced somewhat laterally, so that its axis becomes eccentric to that of the chamber and if the discharge outlet for the purified air is central, or concentric with the axis of the chamber, the function of separating will be interfered with by the encounter of the air of the eccentric vortex with the concentric walls of the air outlet. It is therefore necessary that means be provided for causing the axis of the tubular guard or air outlet tube to register with the axis of the vortex of whirling air. Many unsuccessful or only partially successful efforts have been made to accomplish this object, and one means for doing this is shown in another former application filed by me March 3, 1916, Serial Number 81,695.

It has further been found in machines of this class that in order to prevent the disagreeable buckling and in and out snapping movement of the deck, owing to its size and due to the varying pressure of the inner air against it, that the deck must be either made of very heavy metal, or of wood, both of which are objectionable in many respects.

It is the general object of the present invention to overcome the difficulties enumerated, and to provide an improved machine of this class which will not be open to any of these objections.

A specific object of the invention is to provide means whereby, when the proper location of the air escape has been determined, and the deck secured in position, no further adjustment of the air escape will be necessary and all movable parts of the deck for such adjustment will be eliminated.

A further object of the invention is to provide means whereby, in a machine of this character, the deck may be made of light-

weight, and of cheap metal which at the same time shall not be liable to any of the objections hereinbefore enumerated.

A further general object of the invention is to economize in the weight and cost in machines of this class without detracting from their utility and lasting qualities.

With these enumerated objects in view, and such other objects as may hereinafter appear, the invention consists in the improved construction, arrangement and combination of the parts of a dust collector which will be hereinafter fully described and afterward specifically claimed.

In order that the construction and operation thereof may be readily comprehended, I have illustrated in approved embodiment of my invention in the accompanying drawings and will now proceed to fully and specifically describe the same, having reference to said drawings, in which—

Figure 1 represents a vertical sectional view with the lower conical portion of the separating chamber broken away, in part; Fig. 2, a top plan view, and Fig. 3, a partial central vertical sectional view with the tubular guard or exhaust air tube in a different adjustment from that of Fig. 1.

Like reference characters indicate the same parts in all of the figures of the drawings.

Referring to the drawings, A denotes the separating chamber, which comprises the usual upper cylindrical portion 1, and a lower tapered or conical portion 2, terminating at its lower end in the usual dust discharge opening, not shown. The upper cylindrical portion is provided with the usual tangential inlet passage 3, for the dust laden air, shown in dotted lines in Fig. 1, and 4 represents the tubular guard or air exhaust tube forming an outlet through which the purified air escapes.

The top or deck 5 of the collector is of the usual sheet metal construction, having an opening therein concentrically disposed relative to the axis of the collector, within which opening is supported the tubular guard, to which reference has heretofore been made. This tubular guard is constructed in two main parts, namely, an upper portion 6 extending without the casing or receptacle, and a lower portion 7, depending from the top of the collector and projecting within the separating chamber.

I make the deck 5 of a thin sheet of metal and attach thereto by any suitable means, the tubular guard of which the portion 6 projects above the deck and the portion 7 below the deck and into the interior of the chamber 1.

Angle iron bars 8 have their horizontal portions secured to the deck 5 by means of bolts or rods 9 and their vertical portions secured to the tubular guard by means of

bolts or rods 10, thereby rigidly securing the tubular guard to the deck.

An inverted cone 11 of thin sheet metal surrounds the portion 7 of the tubular guard, being secured by any preferred means, at its upper and lower ends, to the under side of the deck 5 and the lower outer edge of the portion 7 of the tubular guard.

Within the portion 7 of the tubular guard, adjacent to its lower end, I mount an auxiliary portion or extension 12 of the tubular guard by providing it with pivots 13 projecting diametrically on opposite sides and adapted to engage the lower edge of the portion 7 no matter in what position said extension may be turned axially with relation to the portion 7. The extension 12 of the tubular guard 4 has its upper portion, which carries the pivots 13, normally concentric with the parts 6 and 7 but adjustable on said pivots, and separated from the part 7 by a flexible packing 14 but the lower portion of said extension is slightly inclined out of the axial line to accommodate the normal eccentricity of the axis of the vortex of the whirling air and the whole extension is adjustable to accommodate any further eccentricity of said vortex axis which may be found to exist, by means now to be described.

A frusto-conical member 15 is arranged in the upper portion of the tubular guard, being supported therein by means of a peripheral flange 16 which rests on a circular bracket 17 secured within the portion 6 of the tubular guard. The member 15, within the walls of the tubular guard, forms an auxiliary dust chamber, the dust collected therein being conveyed to a suitable place of discharge through a tube 18, such construction being described and claimed in my co-pending applications hereinbefore mentioned.

Within the frusto-conical member 15 and extending transversely across the same, is a strut or bar 19 which is bolted or otherwise secured at its ends to the walls of said member, a smaller strut or bar 20 being provided within the extension 12 of the tubular guard, said strut 20 extending transversely across the extension and being pivoted or otherwise secured at its ends to the walls of said extension. Extending through perforations eccentrically located in these struts with regard to the conical member, are rods or bolts 21 and 22 by means of which the two portions of the tubular guard may be drawn toward each other and the pivots 13 held in contact with the lower edge of the portion 7. By lowering one of these rods and raising the other, the extension 12 may be tilted on said pivots 13 so as to throw the lower end of the extension 12 into a more inclined position and farther out of axial alignment with the chamber 1 in order to accommodate an increased eccen-

tricity which may be discovered in the axis of the vortex of the whirling air. This lateral pivotal adjustment of the extension may be made in any diametrical line by turning 5 the frusto-conical member on the flange 17 of the tubular guard, carrying with it the extension 12 and its supporting rod or struts and changing the diametric position of the pivots 13.

10 While I have specifically described the construction and arrangement of the various parts embodied in my invention as herein illustrated, I desire it to be understood that I do not confine myself rigidly 15 thereto, for the reason that changes and variations might be made therein, without departing from the spirit and scope of the invention, as hereinafter claimed.

Having thus fully described my invention 20 what I claim as new and desire to secure by Letters Patent of the United States is—

1. A dust collector of the cyclone type comprising a separating chamber and a deck therefor, a tubular guard mounted in said 25 deck and an extension on said tubular guard pivotally connected to the guard within said chamber.

2. A dust collector of the cyclone type comprising a separating chamber and a deck 30 therefor, a tubular guard mounted in said deck and an extension on said tubular guard axially adjustable with reference to the guard.

3. A dust collector of the cyclone type 35 comprising a separating chamber and a deck therefor, a tubular guard mounted in said deck and an extension on said tubular guard axially adjustable with reference to the guard and pivotally adjustable thereon.

40. 4. A dust collector of the cyclone type comprising a separating chamber, a deck therefor of light weight sheet metal provided with an air escape opening, a tubular guard mounted in said opening and projecting 45 above the deck, and parallel vertical transverse truss rods secured to the deck and bearing against opposite sides of the tubular guard.

50. 5. A dust collector of the cyclone type comprising a separating chamber, a deck therefor of light weight sheet metal having an air escape opening, a tubular guard mounted in said opening and projecting above the deck, and transverse truss rods 55 comprising vertical portions secured to the opposite sides of the tubular guard and horizontal flanges secured to the top of the deck.

60. 6. A dust collector of the cyclone type comprising a separating chamber, a deck therefor, a tangential entrance to the upper part of the separating chamber for dust

laden air, a tubular guard mounted in the deck and projecting below the same, and an inverted cone of thin sheet metal surrounding the tubular guard, the sides of said cone 65 extending downwardly and inwardly from the deck in position to receive the impact of the incoming dust laden air.

7. A dust collector of the cyclone type comprising a separating chamber and a deck 70 therefor, a tubular guard mounted in the deck, a circular bracket within said guard, a frusto-conical member supported on said bracket, an extension on the tubular guard within the chamber, transverse struts with- 75 in the frusto-conical member and the extension, and adjustable supporting rods connecting the struts.

8. A dust collector of the cyclone type comprising a separating chamber and a deck 80 therefor, a tubular guard mounted in the deck, a circular bracket within said guard, a frusto-conical member supported on said bracket, an extension on the tubular guard within the chamber, transverse struts within 85 the frusto-conical member and the extension and adjustable supporting rods connecting the struts, the extension having diametrically projecting pivots adapted to engage the lower edge of the tubular guard. 90

9. A dust collector of the cyclone type comprising a separating chamber and a deck therefor, a tubular guard mounted in the deck and extending above and below the same, a circular bracket inside of the upper 95 portion of the guard, a frusto-conical member axially adjustable on said bracket, an extension on the lower end of the tubular guard, struts diametrically secured in the frusto-conical member and the extension, 100 pivots projecting diametrically from the extension and adapted to engage the lower edge of the tubular guard, and supporting rods or bolts connecting the two struts on the opposite sides of the diametrical line of the 105 pivots of the extension.

10. A dust collector of the cyclone type comprising a separating chamber and a deck therefor, a tubular guard mounted in the deck, a circular bracket within said guard, 110 a frusto-conical member supported on said bracket, an extension on the tubular guard within the chamber, transverse struts with- in the frusto-conical member and the extension, and adjustable supporting rods 115 connecting the struts, the extension having diametrically projecting rods adapted to engage the lower edge of the tubular guard.

In testimony whereof I affix my signature.

FREDERICK A. WEGNER.
